Patented Mar. 5, 1918.

Arthur Holmes ^{INVENTOR}
By Howard P. Neuman
ATTORNEY

UNITED STATES PATENT OFFICE.

ARTHUR HOLMES, OF CANTON, OHIO.

DESIGN FOR A HOOD-FRONT FOR AUTOMOBILES.

51,841.

Specification for Design.

Patented Mar. 5, 1918.

Application filed January 21, 1918. Serial No. 213,061. Term of patent 3½ years.

To all whom it may concern:

Be it known that I, ARTHUR HOLMES, a citizen of the United States, residing at Canton, in the county of Stark and State of Ohio, have invented a new, original, and ornamental Design for Hood-Fronts for Automobiles, of which the following is a specification, reference being had to the accompanying drawing, forming part thereof.

The figure is a perspective view of a hood

front for automobiles, showing my new design.

I claim:

The ornamental design for a hood front for automobiles, as shown.

ARTHUR HOLMES.

Witnesses:

A. C. BROWNING,
HEMSLEY B. MASSEY.
